(57) **CLAIM**

The ornamental design for a vehicle cup holder expander, as shown and described.

DESCRIPTION

FIG. 1 is a front, right and top perspective view of a vehicle cup holder expander showing my new design;

FIG. 2 is a rear, left and bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a front perspective view of the vehicle cup holder expander shown in an alternate configuration of use;

FIG. 10 is a top perspective view thereof, showing the moving part in a closed position;

FIG. 11 is a bottom perspective view of FIG. 10, showing the bottom part moving to a side; and,

FIG. 12 is a right view of FIG. 10, showing the bottom part moving to a side.

The broken lines shown in the figures are for the purpose of illustrating portions of the vehicle cup holder expander that forms no part of the claimed design.
